PHOTOELECTRIC REGISTRY OF STRIP FILTERS

Ulmer E. Conover, Sayreville, N. J., assignor to Radio Corporation of America, a corporation of Delaware

Application March 25, 1955, Serial No. 496,787

14 Claims. (Cl. 117—211)

This invention relates to color television pickup, or camera, tubes. In particular this invention relates to a method of manufacturing target electrodes for color television pickup tubes.

One type of color television pickup tube comprises an evacuated envelope having an electron gun in one end thereof. The electron gun produces an electron beam which scans a target electrode within the other end of the envelope. The target electrode normally comprises a transparent support member having a large plurality of clusters of color filter strips arranged thereon. Each of the clusters of color filter strips includes one color filter strip that passes one of three primary colors. Extending across each of the color filter strips is a different semi-transparent signal strip. Covering all of the signal strips is a photoconductive layer.

In tubes of the type briefly described above, it is desirable to have the color filter strips in contiguous relation, i. e. in contact, so that substantially no light passes between adjacent color filters. This contiguous relationship is desirable in order to prevent white light from passing between the filter strips and actuating the photoconductive layer. Also, it is desirable that each color filter is contiguous to the adjacent color filter, rather than partially extending over an adjacent filter, in order to provide color purity in the output signal.

It is also desirable in tubes of this type to have the semi-transparent signal strips centrally located on their respective color filter strips. If the signal strips are not centrally disposed, they must be made more narrow to prevent electrical shorts between adjacent strips. When the signal strips are centrally located, larger areas of the target may be utilized for picture reproduction since the signal strips may be made wider, and still be electrically insulated one from the other.

In the past, targets of the type described above have been manufactured by evaporating material through a movable mask comprising a plurality of fine grill wires. The grill wires are moved with respect to the transparent target support plate during the formation of the target to put down portions of the signal strips and the filter strips at the proper places. The movement of the wires relative to the target plate has been measured by means of micrometers. Thus, when a change in location is desired the support plate is moved with respect to the grill wires, by a gear arrangement, until predetermined readings of the micrometers are reached. The micrometer adjustments have been found to be unreliable for several reasons such as, for example, dust particles in the adjustment gearing. The errors in the micrometer adjustments have been found, at times, to be greater than the width of a single color filter strip and much greater than the distance between a pair of signal strips. Other determining factors in inaccurate positioning are the inability of the gear train to repeat settings, and also the physical ability of the operator to consistently make accurate readings of micrometer settings. The inability

of the micrometer to repeat settings is especially pronounced when the step of depositing the signal strips is started. The reason for this is that the masking mechanism must be taken apart to replace one set of grill wires with another set the wires which are of a larger diameter to provide signal strips that are more narrow than the color filter strips. When the set of larger grill wires is used, it must be positioned centrally over the deposited color filter elements.

10 It is therefore an object of this invention to provide a novel method of manufacturing targets which substantially eliminates errors which occur because of inaccurate mechanical adjustments.

15 It is a further object of this invention to provide a novel method of determining the center of an extremely narrow color filter strip.

20 These and other objects are accomplished in accordance with this invention by providing a method of manufacturing a pickup tube target which includes the steps of depositing a first group of color filters spaced apart on a transparent support member; then measuring, by means of photoelectric optical devices, the exact location of the first group of color filters in order to determine the correct position for the second group of color filters; de- 25 positing the second group of color filters; then measuring by means of a photoelectric optically device the location of the second group to determine the position of a third group of color filters; and depositing the third group of color filters. When the color filters have been deposited, 30 the exact center of each of the color filters is determined by photoelectric optical means and a different signal strip is deposited on each color filter in the exact center of each of the color filters.

35 Other features and advantages of this invention will become apparent from the following detailed description when read in conjunction with the accompanying two sheets of drawings wherein:

40 Figure 1 is a sectional view of a pickup tube manufactured in accordance with the methods taught by this invention;

45 Figure 2 is an enlarged fragmentary plan view of the target shown in Figure 1;

Figure 3 is a sectional view taken along line 3—3 of Figure 2;

50 Figure 4 is a sectional view of a means for manufacturing the target in accordance with this invention; and

55 Figure 5 is a perspective view of apparatus utilized to manufacture targets in accordance with this invention.

Although the invention is applicable to various types of devices it will now be described in detail with reference to a color television pickup tube. However, it should be understood that this invention is applicable to other types of devices and particularly to other types of pickup tubes.

55 Referring now to Figure 1 there is shown a sectional view of a color television pickup tube 10 manufactured by methods in accordance with this invention. Pickup tube 10 comprises an evacuated envelope 11 having an electron gun 12 in one end thereof. The electron gun 12 includes the usual cathode 14, control electrode 16, and one or more accelerating electrodes 18. A final accelerating electrode 20 is in the form of a wall coating, and is connected to a potential source (not shown) by means including spring fingers 21 which are supported by, 60 but insulated from, the electron gun 12.

65 An electron beam is produced by the electron gun 12 and is directed toward a target 23 in the other end of the envelope 11. Means are provided for focusing the electron beam, and scanning the beam over the target 23 to form a raster, and may include a focus coil 25, a deflection yoke 27, and an alignment coil 29. A foraminous electrode 31, which is permeable to the electron

beam, is positioned adjacent to target 23 and in operation, together with focus coil 25, functions to insure that the electron beam in its final approach to the surface of target 23, is normal thereto. The target 23, is conventionally supported adjacent to a transparent end of the envelope 11. Terminal pins 33 are sealed through the envelope to connect the target to sources of potential (not shown) and to support the target 23.

The target 23, which is shown in detail in Figures 2 and 3, comprises a transparent support member 35, which may be formed of a separate element as shown, or may be formed by the end of envelope 11. The target support member 35 is arranged normal to the electron beam and has a pair of sets of conductive strips, or bus bars 37 on the surface thereof toward the electron beam. Only one set of bus bars 37 is shown; for simplicity of illustration, with the other set being arranged adjacent to an opposite side of support member 35. Spanning the support member 35, substantially transverse to the bus bars 37, is a plurality of color filter strips 39, 40 and 41. Each of the color filter strips is of an insulating material such as, zinc selenide, zinc sulphide or magnesium fluoride and passes one of three primary colors; e. g. 39 red, 40 blue and 41 green. Centrally located on each of the color filter strips is a semi-transparent conductive signal strip 43. Each of the signal strips 43 is connected to one bus bar 37 in each of the sets of bus bars for the particular color filter under consideration. Covering the signal strips 43 is a photoconductive layer 44, which is shown as partially broken away for simplicity of illustration. As shown by Figure 2 each of the signal strips 43 is insulated from the bus bars 37 for the other colors by means of the electrically insulating color filter strips 40 or 41.

The support member 35 may be any transparent material such as glass. Bus bars 37 may be any conductive material, for example gold, which may be deposited by any known means such as evaporation. Due to the fact that bus bars 37 are remote from the picture reproduction areas of target 23, the bus bars 37 need not be transparent. Color filter strips 39, 40 and 41 may be any of the well known color filters such as interference type filters, or dichroic type filters. In the example of a target shown in Figure 2, the color filters 39, 40 and 41 are electrically insulating. The signal strips 43 are made of any highly conductive material and are semi-transparent to light. One material which is suitable is a film of gold which may be deposited by evaporation. The photoconductive layer 44 may be any material having a spectral response similar to that of the human eye; one example of such a photoconductive material is antimony tri-sulphide.

For best operation it is desirable that each of the color filter strips 39, 40 and 41 be contiguous with the filter strips that are adjacent thereto. Also, for optimum tube operation, each of the signal strips 43 should be centrally located on its respective color filter strip 39, 40 or 41. The color filter strips should be in the contiguous relation in order to eliminate the possibility of white, or unfiltered, light passing between the color filter strips and falling on the photoconductor to produce spurious white signals. Also, for best operation, the color filter strips should not overlap which would cause color mixing in the pictures reproduced by device 10. The useful areas of the photo-conductor 44 are the areas directly over a signal strip 43. Therefore, a maximum width of signal strips is preferred in order to provide high definition to the pictures obtained from the target. Each of the signal strips 43, should thus be centrally located over one of the color filters to provide a maximum width to each signal strip, with sufficient insulation between adjacent signal strips.

Referring now to Figures 4 and 5 there is shown a means for manufacturing targets in accordance with this invention. Specifically, Figure 4 shows a sectional view

of an evacuated bell-jar 46 having an evaporator crucible 48 supported adjacent to a heater element 50. The bell jar 46 may be evacuated by any well known means, not shown. The crucible 48 includes several pockets 51 which are designed to hold the various materials for making a target 23. The pockets of crucible 48 are selectively located, by means of the rotatable arm 49, adjacent to the heater element 50, for depositing particular materials. Supported above the crucible 48 is an evaporator shield 52 which is designed to shield a target support assembly 54 until the selected material in the evaporator has reached the desired temperature so that the amount of material deposited may be accurately controlled. Target support assembly 54 is shown as being greatly enlarged for purposes of illustration.

The target support assembly includes a frame 56, for holding the target support plate 35, that is movably supported upon a grill wire holder 58. The holder 58 supports a large plurality of fine grill wires 60. Arranged beneath the grill wires 60 is a shield 62 for determining, by means of the particular aperture 63, 63', 63" or 64" selected, the length of the strip which is to be evaporated through apertured shield 62 and through the grill wires 60. Thus, strips evaporated through aperture 63 are shorter than strips evaporated through larger aperture 63' etc. As shown in the drawings, frame 56 is movably supported with respect to the grill wires 60 as represented by the arrow 65. Also, shield 62 is movably supported with respect to frame 56 as represented by arrow 67.

Bus bars 37 are laid down by evaporating gold through an appropriate mask onto the target support plate 35. Next, the target support plate 35 is positioned in the support assembly 54 and above the grill wires 60. Then, color filter material in a pocket 51 is heated to evaporating temperature, shield 52 is rotated aside, and a first group of color filter strips 39 is deposited by evaporating the electrically insulating filter materials from the pocket 51 through the grill wires 60 onto the target support plate 35.

The color filter strips 39, 40 and 41 are contiguous with each other in accordance with this invention. When the color filter strips are contiguous, or even when they are only closely spaced, it has been found that insulating material may be scattered from the grill wires 60 into adjacent areas of plate 35. As an example, some insulating material may be scattered, while depositing strips 39, onto the areas of target support plate 35 where it is desired to subsequently deposit color filter strips 40 and 41. Although the small amount of scattered material is not enough to affect the filtering properties of adjacent color filters, it is enough to hinder good electrical connections between the signal strips and bus bars for the adjacent filters. Thus, if color filter strip 41 were deposited first, insulating material therefrom may be scattered onto the intermediate bus bar 37 so that a good electrical connection could not be made between the intermediate bus bar 37 and the signal strip 43 for the color filter 40. This harmful scattering may be eliminated by depositing the materials in the following order: short color filter 39, then its signal strip 43, intermediate color filter 40, and its signal strip 43, and long color filter 41 and its signal strip. This order of deposition eliminates harmful scattering because of the large distances involved between adjacent bus bars 37 as compared to the short distance between a color filter and an adjacent signal strip. Therefore, when the first group of color filter strips 39 has been deposited, the masking frame 58 is removed from bell jar 46 and replaced with one having wires of larger diameter (not shown) for depositing a set of signal strips 43 on the deposited color filter strips 39. When the grill wires are changed, it is desirable to accurately align the central portion of the color filter strips 39 with the spacings respectively between the grid wires of the new mask. This

is necessary in order to deposit a signal strip 43 on the center of each filter strip 39.

In accordance with this invention, the center line of the signal strip mask is aligned so that the space between adjacent wires accurately overlies the center line of one color filter strip 39. This alignment is accomplished by reflecting light from a source 64 through the grill wires 60 and through the deposited color filter strips with a mirror 69. The reflected light is directed into a light measuring device 66 including a photocell. The exact alignment of spacings between the grill wires and the center of the deposited color filter strips is found by moving the target support plate 35, over the wire grill mask with a screw thread adjustment 68. Light passing through the grill wires and the glass plate gives a reading on device 66. As the plate 35 is moved over the grill wires, the light transmission through plate 35 is measured by device 66. The light transmitted passes from a maximum to a sharp minimum reading and back to a maximum, as the grill wires are aligned in turn with a clear portion of plate 35, with a portion coated with filter strips 39, and then with a clear portion, respectively. The fact that the light transmission passes to a sharp minimum indicates the point where the spacings between the grill wires are accurately aligned with the center of the corresponding filter strips. The light from source 64 for a particular measurement is light of the monitoring wavelength, i. e. light of a wave length which the filter is designed to reject. For example, blue-green light is used for red filters 39, green light for blue filters 40, and blue light for green filters 41. With the exact centers of the deposited red color filter located respectively over the centers of the spacings between the grill wires, the signal strips 43 are laid down, by evaporating gold onto the deposited color filter strips 39.

When the signal strips 43 have been deposited on the color filter strips 39, the grill wires are replaced with the original smaller diameter grill wires 60 for depositing the second group of color filter strips 40, i. e. blue. In order to accurately locate the second group of color filter strips 40, the exact center of the deposited strips 39 is found by measuring the minimum light transmission point for the blue-green light as described above. When the exact center of the deposited color filter strips has been found, frame 56 is moved one complete color filter width, i. e. the width of the spacing between adjacent grill wires 60. In a successfully designed target this color filter width is in the order of 1.04 mils. This dimension is not limiting as it should be understood that other widths of color filters may be utilized, as well as color filters of different widths, in accordance with this invention. When frame 56 has been moved the desired amount, a second group of color filter strips is deposited, e. g. blue color filter strips 40. By accurately determining the center of the first deposited group of color filter strips, the second group of color filter strips is accurately deposited in contiguous relationship with respect to each of the color filter strips 39 in the first deposited group of color filter strips.

When the second group of color filter strips 40 has been deposited, the grill wires are replaced and the center of the second group of color filter strips 40 is found by finding the minimum light transmission point for the second group of color filter strips 40, i. e. using the monitoring light of a green color in the example. The center of the color filter strips 40 is found as described above and signal strips 43 are deposited centrally thereon.

After the two groups of color filter strips have been deposited, e. g. color filter strips 39 and 40, and their signal strips 43, the original grill wires are replaced and the third group of color filter strips is located by moving frame 58 with screw 68 until the maximum light transmission is measured by light passing through the remaining uncoated areas. For this measurement white light is utilized. At this setting of screw 68 no further movement

of frame 56 is necessary to deposit the third group of color filter strips 41.

When the maximum light transmission point is found, the third group of color filter strips 41 is deposited at this point. Then the grill wires are changed and the final group of signal strips 43, i. e. for the green, are deposited at the center of the third group of color filters by measuring the minimum light of the monitoring color, i. e. blue light as described above.

10 An alternative method of measuring the location of the first group of color filter strips, in order to deposit the second group of color filter strips, is to vary the position of the support plate to the point where the maximum light transmission through plate 35 becomes constant. 15 At this point the spacings between grill wires 60 are registered with clear areas which are contiguous with the color filters on plate 35. With the frame 56 in this position, the second group of color filters is deposited.

It should be understood that while depositing the first, 20 second and third groups of color filter strips, the apertured shield 62 is positioned so that the correct lengths of each of the groups of color filters is determined by the aperture size selected.

The color filter strips may be deposited before any 25 of the signal strips 43. When this order of deposition is utilized, the location of each of the deposited color filter strips should be determined by this invention before any other group of color filter strips is subsequently deposited. One reason for this is that heat from 30 filament 50 may cause changes in the adjustment mechanism so that predetermined setting of mechanism 68 cannot be depended upon to provide accurate positioning of frame 56 so that contiguous filter strips may result.

Even when all of the color filter strips are deposited 35 before any signal strips 43, it is desirable for optimum operation to accurately position the transparent signal strips 43 on the center of each of the color filter strips. The exact center group of the deposited color filter strips is determined in accordance with this invention by determining the maximum light transmission point for the particular color filter under consideration, i. e. using red light for red filters 39, or by using the minimum light transmission point for the monitoring light as described above.

40 45 Although the invention has been described as relating to a particular type of target for a television pickup tube, it should be understood that it is equally applicable to other types of targets. Also, the invention need not be limited to a grill but may utilize a foraminous mask in 50 which the apertures are in any arrangement. Furthermore, the invention has utility in putting opaque materials through a mask onto a transparent surface. In such a case the mask is accurately registered over the deposited pattern when the light transmission through the 55 support plate and mask is substantially zero.

What is claimed is:

1. The method of manufacturing a target of the type including a plurality of color filter strips each having a different semi-transparent conductor thereon, said method comprising depositing one of said color filter strips through a wire grill onto a support plate, determining the center of said one color filter strip by determining a point of minimum light transmission through said filter, moving the grill with respect to said support plate a predetermined amount and depositing the second of said color filters, determining center of the space between said first and said second deposited color filters by determining the maximum light transmission point therebetween, and depositing a third color filter strip onto the center of said space.

60 65 70 75 2. The method of manufacturing a target of the type including a plurality of color filter strips on a transparent support member and a different conductive signal strip on each of said filter strips, said method comprising the steps of depositing said color filter strips, determining the

center of each of said filter strips by finding the point of maximum light transmission through said filter for light of the same color as said filter strip passes, and depositing a different one of said conductive signal strips on said center.

3. The method of manufacturing a target for a television pickup tube comprising the steps of depositing at least one color filter on a transparent support member, determining the center of said color filter by measuring light transmission through said filter, and depositing a conductive member on said center.

4. The method as in claim 3 wherein the center of said color filter is determined by measuring the minimum light passing through said filter using light of a color which said filter is designed to reject.

5. The method as in claim 3 wherein the center of said color filter is determined by measuring the maximum light passing through said filter using light of a color which said filter is designed to pass.

6. The method of manufacturing a target comprising the steps of depositing a color filter through a mask onto a support member, determining the center of said color filter by measuring light transmission through said filter, moving said mask with respect to said filter a predetermined amount from said center, and depositing a second color filter.

7. The method of manufacturing a target for a television pickup tube comprising the steps of depositing a color filter through a mask onto a support member, moving said mask with respect to said support member to a point where the transmission of white light directed through said mask and said color filter becomes constant, and depositing a second color filter at said point.

8. The method of manufacturing a target for a television pickup tube comprising the steps of depositing a color filter through a mask onto a support member, moving said mask with respect to said support member to a point where the transmission of white light directed through said mask and said color filter becomes constant, depositing on said support member a second color filter at said point through said mask, moving said mask with respect to said support member to a point where the transmission of white light directed through said mask and said target becomes a maximum, and depositing through said mask a third color filter on said support member at said last mentioned point.

9. The method of manufacturing a target for a color television pickup tube comprising depositing a group of color filter strips through a first grill, determining the center of said strips by means of light transmission through a second grill and through said color filter strips, and depositing a different semi-transparent conductor through said second grill onto said center.

10. The method as in claim 9 wherein the center of said color filter strips is determined by finding the maximum light transmission using light of the same color as said filter is designed to pass.

11. The method as in claim 9 wherein the center of said color filter strip is determined by finding the minimum light transmission using light of a color said filter is designed to reject.

12. The method of manufacturing comprising depositing an element on a support member through a mask, determining the center of said element by means of light transmission through a different mask and said element, and depositing a conductive member on said center through said different mask.

13. The method of manufacturing comprising depositing a first element on a support member through a mask, determining the location of said element by moving said mask with respect to said support member to a point where light transmission through said mask and said element becomes constant, and depositing a second element at said point.

14. The method of manufacturing a target for a pickup tube comprising depositing a first, second and third group of color filter strips in contiguous relation on a support member, determining the center of one of said first group of color filter strips by means of light transmission through a grill and through said one of said first group of color filter strips, and depositing a semi-transparent conductive signal strip on said center.
